Patented July 18, 1916.

Inventor,
Frances W. Workman
Edmund S. Shantz
Atty

UNITED STATES PATENT OFFICE.

FRANCES W. WORKMAN, OF LOS ANGELES, CALIFORNIA.

UNDERGARMENT.

1,191,865.

Specification of Letters Patent. Patented July 18, 1916.

Application filed April 19, 1915. Serial No. 22,217.

To all whom it may concern:

Be it known that I, FRANCES W. WORKMAN, a citizen of the United States, residing at Los Angeles, in the county of Los Angeles and State of California, have invented new and useful Improvements in Undergarments, of which the following is a specification.

This invention relates to undergarments 10 for women and pertains especially to an improvement in undergarments having a vest portion of woven fabric and a body portion of knitted fabric, as described and claimed in my patent for undergarments, No. 15 1,128,213, February 9th, 1915.

It is an object of this invention to overcome the objectionable features of undervests, union suits and the like, formed wholly of knitted material, which objections reside in the fact that the knitted shoulder straps have a tendency to slip down on the arm or of the ordinary woven chemise which is often substituted for the knitted garment, but which tends to gather in 25 bunches beneath the corset, by reason of its not conforming to the body.

It is a further object to provide an undergarment which is formed of a vest portion of woven or non-elastic fabric and a body 30 portion of knitted or elastic fabric with a portion which is adapted to conceal the corset, and thereby take the place of a corset cover, and to confine any garment having shoulder straps or any attachment which 35 must be fastened to the corset hook and still worn next the body and under an undergarment.

I attain these objects by the embodiment 40 of my invention illustrated in the accompanying drawing, in which:

Figure 1 is a view illustrating the garment as applied to the body, with parts broken away to show the construction. Fig. 2 is a view of the garment. Figs. 3 and 4 45 are details showing the manner in which the non-elastic fabric is attached to the elastic fabric, Fig. 3 showing the fullness of the non-elastic fabric at its place of attachment with the woven fabric, and Fig. 4 showing 50 the knitted fabric as expanded. Fig. 5 is a section on the line 5—5 of Fig. 2. Fig. 6 is a section through the shoulder strap, showing the loop for the brassière or other garment worn under the undergarment having shoulder straps.

More specifically, 7, indicates the lower

knitted portion of the undergarment which is secured to an upper portion 8 of non-elastic fabric such as muslin or the like.

9 is a portion which is in effect a peplum 60 and forms with the vest portion 8, a corset cover.

The body portion 7 may comprise a body and leg portions of a union suit or the body portion of an undervest, and is adapted to be placed next the body and conform thereto. The body portion 7 is attached to the vest portion 8 at a point immediately below the arms, the vest portion 8 being attached to the body portion so that there is a fullness in the vest portion which will permit 70 expansion of the knitted fabric.

Shoulder straps 10 and 11 comprise a part of the vest portion 8 and due to the fact that they are non-elastic, they will not easily 75 slip down over the shoulders as is the case with a garment which is formed entirely of knitted material.

The peplum portion 9 is preferably an integral part of the vest portion 8. In other words, the vest portion 8 and peplum portion 9 form a corset cover to which the body portion 7 is attached. Draw string 12 or rubber bands are inserted at the waist line.

The garment is placed upon the body in 80 the manner in which the ordinary union suit or undervest is placed thereon and the corset applied over the portion 7 and underneath the peplum portion 9. The peplum portion 9 is then secured over the corset by the draw strings or rubber bands, thus 85 effectively concealing the corset and giving the dainty fullness to the outside waist and not requiring an extra garment for this 90 purpose.

If a brassière or other garment is worn, 95 having shoulder straps or attachments to be fastened to the corset hook, it can be applied next to the body and my improved undergarment placed over it. A tape which is attached to the front of the brassière or other 100 garments as previously described for securing it and preventing it from creeping up, is passed through an aperture 13 in the front of the garment and the attachment at the end of the tape is secured to a hook on the corset. The shoulder straps on the brassière or other garment are secured to the shoulder straps 10 and 11 of the undergarment by 105 passing brassière or other shoulder straps along the underside of the shoulder straps 10 and 11, and looping tape 14 around the 110

brassière shoulder straps, snapping the female clasp member 15 to the male clasp member 16, thus forming a loop and preventing the brassière shoulder strap and the 5 garment shoulder strap from having independent movement on the shoulder.

What I claim is:—

1. An undergarment comprising a corset cover portion formed of non-elastic fabric, 10 an auxiliary body portion secured thereto formed of elastic fabric and hanging loosely under said corset cover portion to form a vest, union suit or other garment intended to be worn next to the body, said corset cover portion having a fullness with respect to said body portion:
2. An undergarment provided with shoulder straps having loops for detachably securing brassière or other garment straps, 15 adapted to be disposed beneath said undergarment.
3. An undergarment provided with shoulder straps having loops for detachably securing brassière or other garment straps, 20 and provided with an aperture at the front disposed to permit the passage of a brassière tape therethrough.
4. An undergarment comprising a corset cover portion formed of non-elastic woven fabric and provided with shoulder straps having loops for detachably securing brassière or other garment straps, a body portion 25 formed of knitted fabric secured to said corset cover at the upper parts thereof.
- 35 5. An undergarment, comprising a corset cover portion formed of non-elastic woven fabric and provided with shoulder straps

having loops for garments disposed beneath said undergarment, a body portion formed of knitted fabric secured at its upper portion to the upper part of said corset cover and provided with an aperture adjacent the 40 waist line through which a garment attachment strap may be passed.

6. An undergarment comprising a vest 45 portion formed of non-elastic woven fabric and provided with shoulder straps having loops for brassière or other garment straps, a body portion formed of knitted fabric secured at its upper portion thereto, the place 50 of juncture of said vest and body portion being disposed immediately below the arms of the wearer, and a peplum portion secured to said vest and body portion adjacent their point of juncture.

7. An undergarment comprising a vest portion formed of non-elastic woven fabric and provided with shoulder straps having loops for garments disposed beneath said undergarment, a body portion formed of 55 knitted fabric secured at its upper portion thereto and provided with an aperture adjacent the waist line through which a garment attachment may be passed, the place of juncture for said vest and body portion being disposed immediately below the arms 60 of the wearer, and a peplum portion secured to said vest and body portion adjacent their point of juncture.

In witness that I claim the foregoing I have hereunto subscribed my name this 2nd day of April, 1915.

FRANCES W. WORKMAN.
